UNITED STATES PATENT OFFICE.

FRANK A. BOWERS, OF NEW BRITAIN, CONNECTICUT, ASSIGNOR TO AUTOSALES GUM AND CHOCOLATE COMPANY, OF NEW YORK, N. Y., A CORPORATION OF NEW YORK.

COIN-CONTROLLED VENDING-MACHINE.

1,072,905.

Specification of Letters Patent. Patented Sept. 9, 1913.

Application filed December 10, 1912. Serial No. 735,986.

To all whom it may concern:

Be it known that I, FRANK A. BOWERS, a citizen of the United States, and a resident of New Britain, Connecticut, have invented 5 certain new and useful Improvements in Coin - Controlled Vending - Machines, of which the following is a specification.

My present invention is an improvement over certain features of invention set forth 10 in the application of Albert D. Grover, Serial No. 720,338, filed Sept. 14, 1912.

The object of my invention is to provide the coin-operated mechanism shown in said Grover application with means for actuating 15 the ejecting shaft into final position independently of the deposited coin in the event that the hand-operated coin-carrier was during the previous operation of the machine not actuated sufficiently to complete 20 the movement of the ejecting shaft. It was found that with the centering means provided for the ejecting shaft it was possible to move the shaft in such a position that the centering means was at dead center. 25 The result of this was that during the next operation of the machine, the deposited coin would not connect with the ejecting shaft, whereby the machine remained out of commission until the ejecting shaft was moved out of dead center position. My 30 present invention obviates this difficulty by means of a device which automatically connects the hand-operated coin-carrier with the ejecting shaft independently of the coin.

In other words, if in a machine provided 35 with my invention, the handle or knob on the outside is operated just so much as to leave the ejecting shaft at dead center, the next operation of the knob or handle automatically causes the shaft to complete its 40 ejecting movement, without the interposition of a coin. This places the coin-receiving portions of the ejecting shaft in proper position to coöperate with the coin-carrier.

In the particular embodiment of my invention illustrated in the drawings, the 45 automatic device for moving the ejecting shaft out of dead center consists of a latch pivoted on the coin-carrier and arranged to be held out of operative position by one of the coin-receiving arms of the ejecting shaft, when the latter is in normal position. However, when the ejecting shaft is allowed 50 to remain at dead center, the latch is in a position to engage one of the arms and

thereby move the shaft into proper position when the coin-carrier is again operated. In the broad aspect of my invention this automatic device may be variously arranged to accomplish the same purpose. 60

In the accompanying drawings Figure 1, shows a longitudinal view in section on line 1-1 of Fig. 2, of a machine embodying my invention, only so much of the machine being shown as is necessary to an understanding of my invention. Fig. 2, is a section on line 2-2 of Fig. 1. Fig. 3, is a plan view in section on line 3-3 of Fig. 2. Fig. 4 is a view similar to Fig. 2 showing the operating lever pulled down to a point where the 70 ejecting shaft remains at dead center; and Fig. 5 is a view similar to Fig. 4 showing the operating lever and the connected coin-carrier partly restored to normal position. 75

In the sides of the casing 1 is journaled 75 the shaft 2 which is at one end provided with the handle or lever 3 for manually operating the shaft. If desired, a wheel or knob may be substituted for the lever. On the shaft 2 is rotatably mounted a sleeve or 80 hollow shaft 4 provided with one or more ejecting fingers 5 adapted to eject the lower-most packages from the magazines. Any suitable ejecting means may be provided on the shaft 4 and I have not therefore deemed 85 it necessary to show in detail any specific form of such means, other than showing the ejecting finger 5 which is arranged to eject the packages 6 from the magazine 7 upon proper actuation of the shaft 4. One 90 end of the shaft 4 is provided with a squared head 8 which is engaged by the free end of the spring 9 secured to the casing by bolts or rivets 10. In the particular embodiment illustrated, the head 8 is shown 95 as having four sides. This is on the supposition that the machine illustrated has four magazines and four ejecting fingers 5. If the number of ejecting fingers is varied, 100 the number of sides on the head 8 is varied accordingly. The head 8 and spring 9 form the center means for the shaft 4 and normally hold the same in the position shown in Fig. 2. To the head 8 is secured a metal 105 spider 11 provided with arms 12. These arms correspond in number and position to the sides of the block or centering head 8. Each of the arms 12 is provided with a horizontal extension 13 having a slot 14. When the shaft 4 is in normal position one 110

of the slots 14 is in alinement with the coin-chute 15, so that the deposited coin will pass from the coin-chute through the alined slot 14 on to the coin-carrier 16 which is rigidly fixed upon the shaft 2. This coin-carrier is the same as that set forth and claimed in the application of Albert D. Grover, Serial No. 720,338, filed Sept. 14, 1912, and does not in and of itself constitute a part of my invention. The coin-carrier 16 is provided with a rigid pin 17 which is adapted to engage the coin at or near the center thereof, and hold the same in operative position on the carrier. The latter is provided with an arcuate extension 18 adapted to support the deposited coin when the coin-carrier is out of normal position. A contractile spring 19 is at one end connected with the coin-carrier at 20 and at the other end to a suitable point 20^a on the machine casing, and holds the coin-carrier in the position shown in Fig. 2.

When a proper coin is deposited, it falls on the coin-carrier 16, with its upper end engaging in the slot 14 of the alined extension 13. The lower edge of the coin rests in the groove or recess 17^a of the coin-carrier. It is clear from Fig. 1 that when the handle 3 is pulled forwardly the pin 17 braces the deposited coin C in position to form a rigid connection between the coin-carrier and the ejecting shaft 4. During this ejecting movement of the shaft 4, the block 8 pushes the spring 9 upwardly and thereby places the same under tension. As soon as the shaft 4 has passed beyond the position shown in Fig. 4, the spring 9 completes the ejecting movement of the shaft and forces the latter in the position shown in Fig. 2. Suitable stops are provided to limit the arc of movement of the handle 3. As soon as the handle is released the spring 19 pulls the coin-carrier back into normal position. During the return movement of the coin-carrier the previously deposited coin either falls into the cash box beneath or it may be temporarily retained by the slot 14. In the latter event the coin will drop by gravity out of this slot during the next operation of the machine, when the arm 12 is moved from horizontal down to a vertical position.

At the lower or rear end of the arcuate extension 18 is pivoted the latch 21 by means of the pin 22. When the coin-carrier and the shaft 4 are in normal position, the latch 21 is held outwardly by one of the coin-receiving arms 12 of the spider 11. In this, its inoperative position, the latch 21 has no effect whatever upon the operation of the coin carrier or the shaft 4. However, when the shaft 4 is left at dead center, as shown in Figs. 4 and 5, the latch 21 is released by the arms 12 when the coin-carrier 65 returns to normal position. When the latch

21 is thus released, the spring 19 forces the same inwardly, so that the free end 23 of the latch 21 engages the adjacent arm 12 when the operating handle 3 is again pulled forwardly. In this way the shaft 4 is moved out of dead center to complete the ejecting movement which was started during the previous operation of the machine. The inward movement of the latch 21 is limited by the lateral lug or shoulder 21^a on the latch. This shoulder lies over the extension 18 of the coin-carrier at 18^a. If a careless purchaser should leave the shaft 4 in the position shown in Fig. 4, he would receive no goods because the ejecting movement was not completed. It will be clear from Fig. 4 that when the shaft 4 is at dead center, the arms 12 are out of coin-receiving position and the next deposited coin would not connect the coin-carrier with the shaft 4. However, this connection is established by the latch 21, so that the purchaser does not lose his coin. Of course, no coin need be deposited to operate the machine after the preceding purchaser has left the shaft 4 at dead center, but the position of the shaft 4 is never indicated to the purchaser, because the handle 3 always flies back to normal position when released.

While I have herein shown one specific application of my invention, it is obvious that the basic idea of my invention as defined in the appended claims may be mechanically carried out in other ways than shown.

Having thus described my invention, what I claim as new and desire to secure by Letters Patent is:

1. In a coin-controlled vending machine, a hand-operated member, a second member normally disconnected from said first member, but adapted to be operatively connected therewith through the medium of the deposited coin, centering means for said second member to complete the final movement thereof, at each operation of the machine, and a device connected with said hand-operated member to actuate said second member into final position in the event that during the previous operation of the machine, said centering means was left in an inoperative position by an incomplete movement of said hand-operated member, said device having no effect on the movement of the second member as long as said centering means actuates said second member into final position.

2. In a coin-controlled vending machine, a hand-operated member, a second member normally disconnected from said first member, but adapted to be operatively connected therewith through the medium of the deposited coin, centering means for said second member to complete the final movement thereof at each operation of the machine, and a pivoted latch carried by said hand-

operated member to actuate said second member into final position in the event that during the previous operation of the machine, said centering means was left in an 5 inoperative position by the incomplete movement of said hand-operated member, said latch having no effect on the movement of said second member, as long as said centering means operates said second member into 10 final position.

3. In a coin-controlled vending machine, a hand-operated member, a second member normally disconnected from said first member but adapted to be operatively connected 15 therewith through the medium of the deposited coin, and a device adapted to automatically connect said hand-operated member with said second member for completing the movement of the latter in the event that 20 during the previous operation of the machine said hand-operated member was not actuated sufficiently to cause complete movement of said second member, said device having no effect on the movements of said 25 second member as long as the latter is actuated into final position.

4. In a coin-controlled vending machine, a hand-operated member, a second member normally disconnected from said first member 30 but adapted to be operatively connected therewith through the medium of the deposited coin, and a pivoted latch carried by said hand-operated member to automatically connect the same with said second 35 member for completing the movement of the latter in the event that during the previous operation of the machine said hand-operated member was not actuated sufficiently to cause complete movement of said 40 second member, said latch having no effect on the movements of said second member as long as the latter is actuated into final position.

5. In a coin-controlled vending machine, 45 a pair of normally disconnected members adapted to be connected together through the medium of the deposited coin, and means for operatively connecting said members independently of the coin when the previous 50 operation of said members was incomplete, said connecting means remaining inoperative as long as said members receive full actuation.

6. In a coin-controlled vending machine, 55 a pair of normally disconnected members adapted to be connected together through the medium of the deposited coin, and a pivoted latch carried by one of said members for operatively connecting the same independently of the coin when the previous 60 operation of said members was incomplete, said latch remaining inoperative as long as the members receive full actuation.

7. In a coin-controlled vending machine, 65 a hand-operated member, a second member

adapted to be actuated by said first member through the medium of the deposited coin, radial arms on said second member and means on said hand-operated member adapted to operatively engage one of said arms 70 and thereby connect the two members together when said second member comes to rest out of normal position, said connecting means assuming an inoperative position toward said arms when said second member 75 is in normal position.

8. In a coin-controlled vending machine, a hand-operated member, a second member adapted to be actuated by said first member through the medium of the deposited coin, 80 radial arms on said second member, and a pivoted spring-pressed latch on said hand-operated member adapted to operatively engage one of said arms and thereby connect the two members when said second member 85 comes to rest out of normal position, said latch assuming an inoperative position toward said arms when said second member is in normal position.

9. In a coin-controlled vending machine, 90 a rotary member, a hand-operated member adapted to actuate said rotary member a predetermined amount through the medium of the deposited coin, and normally inoperative means automatically set into operation to connect said members when said rotary member does not receive its predetermined amount of movement. 95

10. In a coin-controlled vending machine, a rotary member having slotted radial arms, 100 a hand-operated member adapted to receive the deposited coin which rests at the top in the slot of one of said arms, whereby said members become operatively connected through the coin, and the pivoted latch carried by said hand-operated member and so arranged that when said rotary member is in normal position the latch is held back in an inoperative position by one of said arms, but when said rotary member is out of normal position the latch automatically moves into position to engage one of said arms and actuate said rotary member into normal position during the next operation of said hand-operated member. 105

11. In a coin-controlled vending machine, a rotary member, a hand-operated member adapted to actuate said rotary member a predetermined amount through the medium of the deposited coin, and a normally inoperative latch carried by said hand-operated member and arranged to be automatically moved into operative position to connect said members when said rotary member does not receive its predetermined 110 amount of movement.

12. In a coin-controlled vending machine, a rotary operating member, a rotary coin-carrier adapted to actuate said operating member through the medium of the depos- 125

4
ited coin, and a normally inoperative latch on said coin-carrier adapted to be moved automatically into position to engage said operating member when the latter does not receive its predetermined amount of movement.

13. In a coin-controlled vending machine, a rotary member, hand-operated mechanism for actuating the same a predetermined amount through the medium of the depos-

ited coin, and means whereby an incomplete operation of said member causes the same to be actuated without a coin during the next operation of said mechanism.

In witness whereof, I hereunto subscribe 15
my name this 25th day of November 1912.

FRANK A. BOWERS.
